UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

Application filed February 14, 1917. Serial No. 148,529.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

This invention relates to electric switches and is particularly applicable to those of the so-called flush type.

One of the objects of the invention is to 15 provide an efficient and reliable switch mechanism which may be enclosed in a relatively small receptacle for flush mounting.

A further object of the invention is to 20 provide a switch mechanism of the character stated enabling arrangement of the operated contactor for movement in a plane perpendicular to the plane of movement of its push buttons thereby providing for a wide range of play of the contact relative to its 25 co-operating contacts.

A further object is to provide such a switch mechanism with means to positively restrain operation of the movable contact pending the storage of sufficient energy in 30 its operating means to insure an adequate snap action.

Other objects and advantages will herein-after appear.

In the accompanying drawing, wherein is 35 illustrated an embodiment of the invention,

Figure 1 is a side elevational view, partly in section, of the switch;

Fig. 2 is a transverse vertical section substantially on line 2—2 of Fig. 1;

Fig. 3 is a plan view of the interior of the switch from beneath;

Fig. 4 is a fragmentary sectional view of the switch mechanism substantially on line 4—4 of Fig. 2;

Fig. 5 is a similar view showing the parts in an altered position; and,

Fig. 6 is a fragmentary view substantially on line 6—6 of Fig. 2, showing the co-operation of certain elements.

Referring to the drawing, the switch illustrated comprises, in general, an oscillatory contactor 1, an operating member 2 and attached push buttons 3, 4 for actuating said contactor through the intermediacy of an energy storing spring 5, a frame 6 and a

recessed insulating base 7 adapted for flush mounting.

The movable switch elements are carried by the frame 6 which comprises a metallic strip reflexed to form parallel portions 8, 9 60 connected by a transverse portion 10 and having an upstanding portion 11.

The contactor 1 is mounted for oscillation upon the outer parallel portion 9 of the frame by means of a stud 12 said contactor 65 comprising a hub 13, an offset laterally extending actuating lug 14, a limiting lug 15 projecting from the opposite side of the hub, and an upstanding restraining lug 16 located substantially midway between the aforesaid 70 lugs.

The movable contacts of the switch include a pair of contact bars 17, 18 mounted in parallel relation for joint actuation by the contactor 1. Each of the contact bars is 75 provided with a centrally located enlarged hub portion 19 and has its extremities bent to form a pair of resilient integral contacts 20, 21. Each hub portion 19 is bored for mounting upon the stud 12 and is further 80 provided with a peripherally located notch 22 to receive the offset contactor lug 14 and with a slot 23 to circumengage the upstanding contactor lug 16, whereby upon assembly of the aforesaid parts, both contact bars are 85 constrained to move with the contactor 1. The corresponding contacts 20 and 21 of the two bars are furthermore arranged in opposed relation to respectively engage a pair of fixed contacts 24, 25 upon both faces of 90 the latter, for bridging the same in one position of the contactor. In practice, the contact bars 17, 18 are preferably formed from a single blank folded double at 26, while obviously the same may be constructed integral with the contactor 1, if desired.

A pair of stop members 27, 28 are struck up from the metal of the lower portion 9 of the frame to be alternately engaged by the lug 15 of the contactor to limit movement of the latter in either direction.

The operating member 2 comprises a hub 29, a pair of oppositely extending arms 30, 31, a cam member 32 projecting in the plane of said arm and substantially at right angles 105 thereto and an outwardly projecting lug 33 extending at right angles to the plane of the afore-described members. Said operating member is pivoted upon an elongated stud 34 fixed within the upstanding portion 11 110

of the frame 6 whereby said operating member is adapted to oscillate in a plane parallel to such upstanding portion and at right angles to the plane of the contacts. The hel cal spring 5 is coiled about the stud 34 and provided with parallel projecting portions 35, 36 extending one on either side of the lug 33 of the operating member and also similarly engaging the two sides of the actuating lug 14 of the contactor, said lug being enlarged toward its free end to insure retention of said spring extensions thereon. The path of movement of the cam member 32 intercepts that of the contactor restraining lug 16 to control the movement thereof as hereinafter described.

The push buttons 3, 4 are secured to the respective lateral extensions 30, 31 of the operating member 2 by means of lost motion connections including pins 37, 38 fixed in the latter and extending respectively through a pair of transverse slots 39, 40 in extensions 41, 42 of said push buttons and headed therebeyond. Said extensions are formed with straight sides 43, 44 adapted to abut and wipe the corresponding edges of the upstanding frame portion 11, thus tending to guide the push buttons during reciprocation thereof. Each of said push buttons is further cut away, as at 45, in Fig. 1, to prevent interference by the contacting member when the push button is depressed.

The base 7 is rectangular in shape and provided with a chamber 46 to receive and house the switch mechanism, and is further provided with a shoulder 47 to receive the frame 6 and with suitable openings 48, 49 in its front or upper face through which extend the push buttons 3, 4. Attachment lugs 50, 51 are inset within the front face of the base 7 and extend therebeyond, being secured thereto by means of screws 52, while a suitable face plate 53 having push button openings 54, 55 is secured to said base by means of screws 56 entering said attachment lugs. The switch fixed contacts 24, 25 are anchored within the base 7 and are provided with suitable conductor terminals 57, 58. The frame 6 is secured upon the shoulder 47 within the base by means of a screw 59 whereby the switch mechanism is retained in suitable operative position. A closure plate 60 preferably of insulating material, is inset within the bottom of the base 7 and secured therein by the screws 52.

The operation of the above described switch is as follows: Upon pressure being applied to either of the push buttons the operating member is swung upon its pivot, causing the lug 33 to move one of the spring extensions 35, 36 in a direction to tension the spring, the opposite spring extension being held against movement by its engagement with the lug 14 of the contactor. The contactor itself is retained against move-

ment by the engagement of the upstanding lug 16 against the cam member 32, thus insuring storing of energy in the spring 5 until the operating cam 32 has been moved sufficiently to release the contactor lug 16, whereupon the contactor and its attached contacts are moved with a snap action due to the stored energy of the spring 5 to contact making or breaking position, the movement of said contactor being arrested by engagement of the lug 15 against one of the stops 27, 28.

The shape of the cam 32 is such as to insure retention of the contactor during energy storing movement of the operating member in either direction and release of said contactor just prior to the termination of movement of the former, while the stops 27, 28 are so located as to insure stopping of the contactor in suitable positions for making and breaking circuit respectively.

What I claim as new and desire to secure by Letters Patent is:

1. The combination in an electric switch, of a contactor movable in a plane and having contacts to engage and bridge suitable fixed contacts, an operating member for said contactor movable in a plane at right angles to the plane of movement of the latter, an energy storing connection between said contactor and said operating member, said contactor and said operating member having parts co-operating to insure storing of energy in said connection and subsequent snap movement of said contactor. 100

2. In an electric switch, in combination, a movable contactor, an operating member movable at right angles to the direction of movement of said contactor, an energy storing connection therebetween, a lug on said contactor, a cam carried by said operating member for co-operating with said lug to restrain said contactor against movement during storing of energy in said connection and to thereafter release said contactor for snap movement thereof in either direction, and means limiting the movement of said contactor. 110

3. The combination in an electric switch, of a supporting frame, a contactor and contacts arranged for snap movement, an operating member for said contactor mounted upon said frame, a push button having an extension attached to said operating member, said extension having an exterior portion to co-operate with an exterior portion of said frame for guiding said push button during movement thereof. 115

4. In an electric switch, in combination, an oscillatable contactor, an operating member, movable in a plane at right angles to the plane of oscillation of said contactor, an energy storing connection between said contactor and said operating member, a lug on said contactor, a cam carried by said oper- 130

- ating member for co-operating with said lug to restrain said contactor against movement during storing of energy in said connection and to thereafter release said contactor for snap movement thereof.

5. In an electric switch, in combination, an oscillatable contactor, an operating member movable in a plane at right angles to the plane of oscillation of said contactor, an energy storing spring associated with said operating member, a lug on said operating member, a lug on said contacting member contiguous to said first mentioned lug, said spring having portions extending on either side of said lugs whereby movement of said operating member tends to produce movement of said contactor, and means for restraining said contactor subject to release by movement of said operating member.

10. The combination in an electric switch, of a supporting frame having portions extending at right angles to each other, a contactor and contacts mounted for snap movement upon one portion of said frame, an operating member for said contactor mounted upon the other portion of said frame, a pair of push buttons having extensions attached to said operating member, the edges of said extensions engaging the adjacent edges of said frame for guiding said push buttons during movement thereof.

15. The combination in an electric switch, in combination, a recessed insulating base having an interiorly located shoulder, a switch frame having parallel portions and an upstanding portion, a self-contained switch mechanism carried by said frame one of said parallel portions of said frame being adapted to abut said shoulder with said upstanding portion extending beyond the latter and releasable means for securing said parallel portion to said shoulder while permitting unitary removal of said frame and switch mechanism from the recess of said base.

20. The combination in an electric switch, in combination, a recessed insulating base having push button openings extending therethrough, a retaining shoulder within the recessed portion of said base, a frame having parallel portions and an upstanding portion to be secured within the recessed portion of said base, and a push button switch mechanism carried by said frame and insertable within said base with its push buttons projecting through the openings therein, and releasable means for securing a parallel portion of said frame upon said shoulder.

25. The combination in an electric switch, in combination, a recessed insulating base having push button openings therein, a retaining shoulder located interiorly of said base, a supporting frame having an upstanding portion and parallel portions certain of the latter being adapted to cooperate with said shoulder, a push button snap switch mechanism mounted upon

30. said frame and insertable therewith within said base with its push buttons projecting through said openings, releasable means for securing such parallel portion of said frame in position upon said shoulder and a closure plate for the recess of said base.

35. The combination in an electric switch, in combination, a recessed insulating base having a shoulder, a rigid supporting frame having parallel portions and an upstanding portion extending at right angles thereto, a switch contactor mounted upon a parallel portion of said frame, an operating member mounted upon said upstanding portion of said frame, an energy storing connection between said contactor and said operating member and means on said operating member and said contactor for restraining the latter during storing of energy in said connection and thereafter releasing said contactor for snap movement in either direction and releasable means co-operating with a parallel portion of said frame for securing the same in position upon said shoulder.

40. The combination in an electric switch, in combination, a supporting frame having parts extending at right angles to each other, an oscillatable operating member mounted upon one portion of said frame, an oscillatable contactor mounted upon the other portion, an energy storing connection between said operating member and said contactor, a lug on said contactor, a cam on said operating member for engaging said lug to restrain said contactor during storing of energy in said connection and thereafter release the same for snap movement, a second lug on said contactor and a stop on said frame to be engaged by said lug for determining the final position of said contactor.

45. The combination in an electric switch, in combination, a rigid supporting frame, an operating member and a contactor mounted on said frame for oscillation upon axes at right angles to each other, an energy storing connection for said operating member and said contactor, a cam on said operating member co-operating with a suitable lug on said contactor during movement of said operating member in either direction to prevent movement of said contactor during the storing of energy in said connection and to thereafter release said contactor for corresponding snap movement thereof in either direction.

50. The combination in an electric switch, in combination, a rigid supporting frame, an operating member and a contactor mounted on said frame for oscillation about axes at right angles to each other, an energy storing connection for said operating member and said contactor, a cam on said operating member co-operating with a suitable lug on said contactor during movement of said operating member in either direction to prevent movement of said contactor during the storing of energy in said connection and to thereafter release said contactor for corresponding snap movement thereof in either direction.

55. The combination in an electric switch, in combination, a rigid supporting frame, an operating member and a contactor mounted on said frame for oscillation about axes at right angles to each other, an energy storing connection for said operating member and said contactor, a cam on said operating member co-operating with a suitable lug on said contactor during movement of said operating member in either direction to prevent movement of said contactor during the storing of energy in said connection and to thereafter release said contactor for corresponding snap movement thereof in either direction.

60. The combination in an electric switch, in combination, a rigid supporting frame, an operating member and a contactor mounted on said frame for oscillation about axes at right angles to each other, an energy storing connection for said operating member and said contactor, a cam on said operating member co-operating with a suitable lug on said contactor during movement of said operating member in either direction to prevent movement of said contactor during the storing of energy in said connection and to thereafter release said contactor for corresponding snap movement thereof in either direction.

65. The combination in an electric switch, in combination, a rigid supporting frame, an operating member and a contactor mounted on said frame for oscillation about axes at right angles to each other, an energy storing connection for said operating member and said contactor, a cam on said operating member co-operating with a suitable lug on said contactor during movement of said operating member in either direction to prevent movement of said contactor during the storing of energy in said connection and to thereafter release said contactor for corresponding snap movement thereof in either direction.

energy in said connection and to thereafter release said contactor for corresponding snap movement thereof, an additional lug on said contactor, a pair of stops on said frame to be alternately engaged by said last mentioned lug for limiting movement of said contactor in either direction.

14. In an electric switch, in combination, a frame, a contactor and an operating member mounted on said frame for oscillation about axes at right angles to each other, energy storing means in the connection between said contactor and said operating member, said contactor comprising a centrally bored hub, a lug extending laterally therefrom for engagement by an extension of said energy storing means, an oppositely extending lug for engagement with suitable limiting means, and an upstanding lug to be releasably engaged by a portion of said operating member to restrain movement of said contactor, and electrical contacts carried by said contactor.

15. In an electric switch, in combination, a movable switch contactor a relatively movable operating member therefor and an energy storing and releasing connection therebetween, said connection consisting of elements carried by said contactor and said operating member respectively for movement in planes at right angles to each other and a resilient member to engage said elements.

16. In an electric switch, in combination, a movable switch contactor, a relatively movable operating member therefor and an energy storing connection therebetween, and releasable restraining means for said contactor comprising co-operating parts carried by said contactor and said operating member respectively for relative movement in planes at right angles to each other.

In witness whereof, I have hereunto subscribed my name.

CHARLES J. KLEIN.
